TOY PISTOL

Robert B. Dickson, Cleveland, Ohio

Application October 18, 1950, Serial No. 190,716

2 Claims. (Cl. 124—27)

1

This invention relates to a toy, and more particularly to a toy pistol.

The object of the invention is to provide a toy pistol that resembles in configuration an actual pistol, the toy pistol of the present invention adapted to shoot small pellets upon proper actuation thereof.

Another object of the invention is to provide a toy pistol which will provide recreation or amusement to the user, the toy pistol being constructed so that pellets can be fired or discharged one at a time.

A further object of the invention is to provide a toy pistol which is extremely simple and inexpensive to manufacture.

Other objects and advantages will be apparent during the course of the following description.

In the accompanying drawings forming a part of this application and in which like numerals have been used to designate like parts throughout the same:

Figure 1 is a longitudinal, vertical sectional view taken through the toy pistol of the present invention, and having one side or section removed to further illustrate the mechanism contained therein;

Figure 2 is a top plan view of the toy pistol of the present invention;

Figure 3 is a sectional view taken on the line 3—3 of Figure 1;

Referring in detail to the drawings, the numeral 10 designates a body which has the exterior configuration of a pistol, the body 10 including a pair of identical sections 11 which are maintained in assembled relation by suitable securing elements, such as pins 12.

The upper front end of the body 10 is shaped to define a chamber or compartment 14 which is adapted to hold a plurality of spherical pellets or balls 15, and the balls 15 are adapted to be shot or propelled when the toy pistol is actuated, as later described in this application. A thumb screw 16 is arranged in threaded engagement with the front of the body 10 and the screw 16 normally closes the chamber 14, but the screw 16 can be readily unscrewed and removed when additional pellets 15 are to be placed in the chamber 14.

Arranged below the chamber 14 is a partition 17, and extending below the partition 17 is a hollow, open-ended tube or barrel 18. The barrel 18 is provided with an opening 19, Figure 1, in its rear end, whereby pellets 15, one at a time, can pass from the chamber 14 into the barrel 18. The body 10 is further provided with a front sight 20 and a rear sight 21.

2

A pin 22 pivotally connects a cocking lever 23 between the sections 11 of the body 10, there being a lip 24 arranged on the lower end of the cocking lever 23 for a purpose to be later described. Secured to the rear of the cocking lever 23 by suitable securing elements, such as screws 25, is a spring member 26. A firing pin 27 is secured or mounted on the upper end of the spring member 26, and upon actuation of the pistol, the firing pin 27 will spring or move forwardly and into engagement with the rear open end of the barrel 18, whereby a pellet positioned in the barrel 18 will be propelled or discharged out of the front of the barrel 18.

A pin 28 pivotally connects a dog or trigger helper 29 between the sections 11, and the dog 29 is cut away to define a shoulder 30 for at times receiving the upper end of the spring member 26. The dog 29 is further provided with a cutout or recess 31 for receiving therein the upper end of an L-shaped trigger 32. A pin 33 pivotally connects the other end of the trigger 32 between the sections 11. Secured to the body 10 by a screw is a body member 34, and the body member 34 has a recess 35 therein, and a coil spring 36 has one end seated in the recess 35. The other end of the coil spring 36 bears against the trigger 32 and is circumscribed on a guide pin 37.

Arranged in the lower end of the body 10 is a support member 38, and the support member 38 is provided with a recess 39 for receiving the upper end of a coil spring 40. The lower end of the coil spring 40 bears against the upper rear surface of a lever lock 41, and the lever lock 41 is pivotally mounted on a pin 42. The lever lock 41 is provided with a cutout or shoulder 43 for selectively engaging the lip 24 on the lower end of the cocking lever 23.

In use, the thumb screw 16 is first unscrewed and a plurality of the pellets or balls 15 are inserted into the chamber 14. Next, the front end of the lever lock 41 is depressed or moved downwardly by means of the user's little finger so that the lever 23 will pivot in a clockwise direction about the pin 22, Figure 1. A spring member 44 is connected to a pin 45 by a set screw 46, and the spring member 44 bears against the lower end of the lever 23 to urge the lever 23 in a clockwise direction when the lever lock 41 is depressed, as above described. Next, the upper end of the spring member 26 is arranged in engagement with the shoulder 30 on the trigger helper or dog 29, and then the cocking lever 23 is returned to the position shown in Figure 1. With the parts in this position, the pistol is now cocked and is ready to be used for

shooting the pellets 15. To shoot one of the pellets 15, the trigger 32 is squeezed against the body 10 so that the spring member 26 will be released from engagement with the dog 29, whereby the firing pin 27 will move from the solid line position of Figure 1 to the broken line position of Figure 1, so as to propel or discharge one of the pellets 15 through the barrel 18. It is to be noted that the pellets 15 feed by gravity from the chamber 14 to the rear end of the barrel 18. After the pellet 15 has been shot or fired, the previously-described cycle is repeated and the pistol is again cocked so that it can be used for firing additional pellets.

A spring member 47 has one end connected to the barrel 18 by a pin 48, while the other end of the spring member 47 is bent and projects through the opening 19 in order to prevent the pellets 15 from accidentally rolling out of their proper position. Also, the chamber 14 can be of sufficient size to hold a large quantity of pellets 15. Portions of the exterior surface of the large body 10 can be knurled so as to facilitate gripping thereof, and the body 10 may be painted any desired color.

I claim:

1. In a toy pistol, a hollow body including a pair of sections connected together, there being a chamber in said body for holding a plurality of pellets, a hollow barrel arranged below said chamber and adapted to receive pellets from the latter, a cocking lever pivotally arranged between said sections, a spring member having one end connected to said cocking lever, a firing pin mounted on the other end of said spring member, and manually operable means for releasing said spring member, said means comprising a locking

dog pivotally connected to said body, and a trigger pivotally connected to said body for causing pivotal movement of said locking dog, there being a recess in said locking dog for receiving the upper end of said trigger.

2. In a toy pistol, a hollow body including a pair of sections connected together, there being a chamber in said body for housing a plurality of pellets, a hollow barrel arranged below said chamber and adapted to receive pellets from the latter, a cocking lever pivotally arranged between said sections, a spring member having one end connected to said cocking lever, a firing pin mounted on the other end of said spring member, and manually operable means for releasing said spring member, said means comprising a locking dog pivotally connected to said body, and a trigger pivotally connected to said body for causing pivotal movement of said locking dog, and a lever lock arranged in the bottom of said housing for maintaining the cocking lever immobile in cocked position, there being a recess in said locking dog for receiving the upper end of said trigger.

ROBERT B. DICKSON.
